M. T. MORGAN

INCUBATOR

Filed April 17, 1922

Inventor
Morgan T. Morgan

By Richard B. Owen.

Attorney

UNITED STATES PATENT OFFICE.

MORGAN T. MORGAN, OF ANACONDA, MONTANA.

INCUBATOR.

Application filed April 17, 1922. Serial No. 553,369.

To all whom it may concern:

Be it known that I, MORGAN T. MORGAN, a citizen of the United States, residing at Anaconda, in the county of Deerlodge and 5 State of Montana, have invented certain new and useful Improvements in an Incubator, of which the following is a specification.

This invention is an incubator and has for 10 its principal object the production of a device which will facilitate the removal of the egg trays from the interior of the incubator without necessitating the opening of a door which would allow the heat to escape from 15 the interior of the incubator.

Another object of this invention is the production of an incubator wherein a tray supporting frame is provided, this supporting frame being removable, whereby the 20 lower portion of the main housing, or heat chamber, is open, thus allowing the tray to be movably supported, whereby when so desired, the tray may be lowered to allow access thereto, without necessitating the 25 opening of a door at the upper portion of the main housing, thus preventing unnecessary escape of the heat from the housing.

Another object of this invention is the production of an incubator wherein the tray 30 supporting frame is provided with a lifting mechanism, thus permitting the tray to be carried within the main housing, at which time, it will constitute a closure for the lower portions of the housing, or when desired, the tray may be lowered to permit 35 access thereto.

Another object of this invention is the production of an incubator including a movable tray supporting frame, this frame being 40 so constructed as to carry trays in convenient position to allow access to the trays when the frame is lowered, thus preventing the escape of the heat in the upper portions of the main housing.

One practical form of construction and assembly of the present invention will be hereinafter described and is illustrated in the accompanying drawing, in which—

Figure 1 is a top plan view of the incubator,

Figure 2 is a front elevation of the device, and

Figure 3 is an elevation of the tray carrying frame.

In the preferred embodiment of the present invention, about to be described, it will

be seen that the main housing comprises a top 5 having side walls 6. The corner standards 7 are connected to the side walls 6 although the standards project for a considerable distance below the lower portions of the walls and constitute a support for the main frame.

It will be noted, by referring to Figure 2 that the lower portion of the main housing is open and thus allows the tray carrying frame to be hereinafter described to be moved into or out of the housing, as desired.

One of the walls 6 is provided with a sight opening 8 having a glass panel 9, thus 70 permitting a view of the interior of the main housing when desired. It will further be noted that the wall is also provided with an enlarged opening 10, whereby egg trays may be removed from or inserted 75 within the housing which constitutes the heat chamber, as shown in Figure 2. It is of course obvious that any form of a door or closure, not being deemed necessary to be herein illustrated may be employed for 80 closing the opening 10.

The tray carrying frame comprises a pair of parallel supporting beams 11, upon which are carried the boards 12, as shown in Figures 2 and 3, wherein a closure is provided 85 for the bottom of the housing, when the frame is carried therein. The supporting walls 13 are carried by the beams 11 and these walls extend parallel to each other. The reinforcing cleat 14 may be secured to 90 the supporting walls 13, as shown in Figure 3, thus holding the walls from spreading or collapsing and for this reason causing the walls to be retained in their correct positions at all times. It will further be noted 95 that the supporting strips 15 are carried upon the inner surfaces of the supporting walls 13, the strips of one wall being in horizontal alignment with the strips of the remaining wall. Accordingly, an egg tray 16 100 may be placed upon each pair of strips, as shown in Figs. 2 and 3, and thus be removably supported upon the tray carrying frame.

The I bolts 17 are carried at the ends 105 of the beams 11 and are retained in adjusted position by the nuts 18. The drum 19 has caps 20 carried upon its ends which are held against displacement by the pins 21. The stub axles 22 extend from the caps 20 110 and project through the bearings 23, fixed as indicated at 24 upon the top 5 of the

main housing. Therefore, it will be seen that the drum 19 is rotatably supported. It will be noted that the crank 25 is connected to one of the stub axles 22, as illustrated in Figures 1 and 2, and for this reason when the crank 25 is swung it will also rotate the drum 19. In order to hold the drum against rotation in one direction, there is provided a ratchet wheel 26 secured adjacent one of the caps 20 and this ratchet wheel is engaged by the pawl 27 mounted upon the ears carried by one of the bearings 23, as shown at 28.

Guide pulleys 29 are carried by the castings 30 adjacent the side edges of the top 5 of the housing, it being noted that the pulleys are carried in alignment with each other, as illustrated in Figures 1 and 2. Cables 31 pass through the drum 19 or may be secured thereto in any desired manner and also pass around the guide pulleys 29. The ends of these cables 31 are connected to the I bolts 17, as shown in Figure 2.

When this invention is in use, the drums 25 may be rotated in one direction after the pawl 27 has been released from engagement with the ratchet wheel 26. Therefore, the cables 31 will lower the egg tray carrying frame. Before such action takes place, it is obvious the interior of the main housing may be viewed through the sight opening and then the frame may be lowered to allow of access to the desired tray 16 carried upon the tray carrying frame. As access to the tray may be had through the opening 10, it is obvious the trays may be removed and another tray inserted in lieu thereof, or the eggs carried by the tray may be partly removed, or in fact any other operation desired may be performed. It is obvious the frame may be lowered as far as desired by the release of the cables by the drum 19.

During this movement, it is obvious that the movement of the frame downwardly from the lower portions of the main housing, will obviate the necessity of a door in the top of the main housing which would allow the heat in the main housing to escape. Therefore, the housing may have a comparatively even temperature, for the necessary operation in connection with the turning of the eggs in connection with ordinary incubators will take place at the lower portion 55 of the device and thus the heat within the upper portions of the housing will be retained.

After the desired operation has taken place, the drum may be rotated in the opposite direction and the cables 31 are wound upon the drum and pass upwardly over the guide pulleys 29 and thus lift the beams 11.

Therefore, as the beams 11 are lifted it is obvious the tray carrying frame may be moved into the interior of the housing, or into the heat chamber thereof, as hereinbefore explained. The boards 12 will constitute a solid closure for the bottom of the main housing, after the frame has been returned thereinto and for this reason heat is positively prevented from escaping to any great degree by the closing of the lower portion of the housing.

It is obvious that any form of a closure may be employed for the opening 10, as hereinbefore explained whereby the incubator will operate in the usual manner.

From the foregoing description, it will be seen that an incubator has been provided wherein the egg carrying frame is removably mounted, thus permitting the same to be lowered from the bottom of the main housing when access is desired to the tray.

Accordingly, an unlimited escape of the heat carried within the housing is prevented while the cables connected to the frame will be easily actuated for the moving of the tray either into or out of the housing by the rotation of the drum 19.

The foregoing description and the drawings have reference to what may be considered the preferred, or approved, form of my invention. It is understood that I may make such changes in construction and arrangement and combination of parts, materials, dimensions, et cetera, as may prove expedient and fall within the scope of the appended claim.

Having thus fully described my invention, what I claim as new and desire to secure by Letters Patent, is:—

An incubator comprising a main housing including a top wall, side walls, and a vertical movable bottom wall, supporting legs for the main housing extending below the lower surface thereof and forming a guide for the lower wall, an upstanding frame carried by the lower wall adapted to extend into the main housing, a sliding egg supporting tray associated with the frame, the lower wall being extended beyond the side walls of the housing and the legs and provided with supporting eyes, a transversely extending rotatable drum carried by the top wall and disposed at a point equi-distant from the ends thereof, means for rotating the drum, the guide pulleys carried by the top wall and arranged on each side of the drum, and lifting cables secured to the extended portions of the lower wall and trained about said pulleys and secured to the drum, as and for the purpose specified.

In testimony whereof I affix my signature.
MORGAN T. MORGAN.
